UNITED STATES PATENT OFFICE.

DAVID MCNAIR, OF BOSTON, MASSACHUSETTS, ASSIGNOR TO ROXBURY CARPET COMPANY, OF SAME PLACE.

DESIGN FOR CARPET.

SPECIFICATION forming part of Design No. 11,843, dated July 6, 1880.

Application filed June 7, 1880. Term of patent 3½ years.

To all whom it may concern:

Be it known that I, DAVID MCNAIR, of Boston, in the county of Suffolk and State of Massachusetts, have invented a new and original Design for Carpets, of which the following is a specification.

My present design is fully illustrated in the accompanying photograph, forming part of this specification, and to which reference is 10 hereinafter made.

My design consists of the complex barbaric figures A, too complicated to admit of detailed description, arranged in parallel rows on a plain ground and preferably connected at their adjacent angles, as shown.
